MECHANISM FOR MANUFACTURE OF TUBULAR PAPER STRUCTURES

David C. Spaulding, Jr., Cleveland, Ohio, assignor
to The Standard Oil Company, Cleveland, Ohio,
a corporation of Ohio

Application July 1, 1937, Serial No. 151,419

5 Claims. (Cl. 91—37)

In the manufacture of tubular structures from paper or the like, in connection with, or rather just after the wall of the structure has been built up, it is generally desirable to treat the exterior surface for finishing or water proofing or otherwise rendering it more resistant than the normal cellulosic surface. Particularly where a rapid through-put of articles is important, it is desirable that each operation be accomplished with such speed and correlation with the other operations as to not retard the general rate of throughput. In accordance with the present invention, mechanism is now provided, which makes possible such treatment of the exterior of structures on the order noted, with very effective results and particular operating convenience.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1, together with its portion Fig. 1a broken out on account of space limitation, is a side elevational view showing structure embodying the invention; Fig. 2 is a fragmentary plan view of the right end thereof, on enlarged scale; and Fig. 3 is a transverse section taken on a plane substantially indicated by line III—III, Fig. 1.

Referring more particularly to the drawing, there is shown a framing *f*, with a forming and forwarding mandrel *2*, driven rotarily intermittently, in brief periods of rotation during which the tube is wound up and formed by the forming mechanism *F*, the details of which may be of any usual or preferred character and need not be particularized here, and driven by driving means which may include a drive motor *m* and intermittently operating gearing *g*, the precise detail of which may be of any desired or preferred character. In association with the mandrel is a forwarding collar or ejector *4* which is reciprocable axially of the mandrel, and in relation with the rotation periods thereof is driven to move axially of the mandrel in excursion of a length sufficient to push the formed tube immediately in front of it a step forward on the mandrel, and being then returned to its initial position leaving the mandrel clear for winding up another tube. The operating means for the ejector may for instance include a cam *10*, on a counter-shaft *11*, for actu-

ating a lever *12* pivoted above to the framing and connected by a link *13* to a lever *14* pivoted below to the framing, and the lever *14* connects through a link to a slide *16* which carries the ejector. In association further with the mandrel, beyond such zone of formation of the tubes, the finishing mechanism whose detail is more particularly here concerned, is positioned such as to in turn operate on the forward tube. The shaft *18* extending along a lower level than the mandrel *2*, for convenience, is driven in connection with the general gearing *g*, and it is correlated with the drive of the mandrel. On the shaft is a cam *19* having a peripheral rise, and extending from a point of pivot-mounting on framing opposite said cam is a fork *20* which carries on the side of its upper limb a roller *21*; and on the side of its lower limb there is a roller *35* to contact with the cam, whereby the fork is oscillatively lowered each time the cam is rotated by the shaft *18*, the fork *20* being urged upwardly especially by resilient means, as for instance a spring *22* extending to a fixed point on the framing. Extending upwardly from the fork *20* is a link *23*, and this is connected by a short arm *24* to a rock shaft *25*. Oscillating with the movements of the rock shaft is an arm *26* which carries a liquid applicator, preferably in the form of a flattened brush *27*, the mounting being such as to bring the latter into contact tangentially against the surface of the rotating article on the mandrel, and the direction of rotation being away from the position of the brush. By reason of the oscillative movement of the brush as determined by the rock shaft and cam-operated link *23*, the lower position of the brush provides for dipping into liquid in the receptacle *30* therebelow. If a heating means, as for instance heating pipes *31* supplied by steam, be included the temperature of the receptacle *30* may be maintained for a liquid condition in material of melting point such that having been applied and distributed over the surface of the tubular article being operated upon, the cooling on exposure rapidly sets the liquid. Among substances which may thus be applied, are wax compositions, etc., which may be of a character to impart more or less polish if desired, or other character of color or finish or surface effect. Carried also on the shaft *18*, but not fixed thereto, alongside the cam *19*, is a thin cam *33*, and projecting out therefrom is an operating handle or hand lever *34*, capable of rocking the cam *33* into position to engage or disengage with the roller *35* on the lower limb of the fork *20*, the roller being of sufficient length to cooperate with

both cams. When the hand lever 34 is in its lowest position, the cam 33 is disengaged from the fork, and the latter is correspondingly free to be operated normally by the spring 22 and cam means 19 as driven by the shaft. When however, the hand lever 34 is raised into its upper position, its cam 33 engages the roller 35 of the fork and holds it down, and irrespective of rotation of the cam 19, the applicator 27 is held in a depressed position away from contact with the tubular structure on the mandrel.

The operation of the apparatus will be clear from the foregoing. A tube having been formed at the forming station, as need not be detailed, and being then ready for the further treatment, the forming collar 4 is slid on the mandrel to the right, as viewed in Fig. 1, by the action of the cam 10 on the cam lever 12, throwing the lever 14, through the connection link 13, and correspondingly pushing the support-slide 16 carrying the forwarding collar 4. The cam 10 then returns the collar 4, and the tube which was forwarded by it is left in position opposite the brush 27. Thereupon, the cam 19, through the intermediary of the upper arm of the fork 20 and the arm 23 actuating the rock shaft 25, raises the brush 27 from the liquid in the pan 30 into contact with the surface of the tube on the mandrel, and the tube being rapidly rotated 30 receives a smooth application of the finishing liquid. The cam 19 then returns the brush down into the liquid in the pan. The forwarding collar 4 again reciprocates toward the right, as viewed in Fig. 1, and thereby forwards a newly formed tube, pushing the now-treated tube ahead of it, and in succession a series of tubes are treated and pushed along by stages to discharge from the mandrel. When for any reason it is desired to interrupt the application of the liquid 40 by the brush 27, the operator may swing the hand lever 34 into its upper position, thereby forcing its cam 33 against the roller 35 of the lower arm of the fork, and thus pulling the arm 23 and the brush 27 down into lower position.

45 Other modes of applying the principle of the invention may be employed, change being made as regards the details described, provided the features stated in any of the following claims, or the equivalent of such, be employed.

50 I therefore particularly point out and distinctly claim as my invention:

1. In apparatus of the character described having a rotatable mandrel, a forwarding collar reciprocable along said mandrel, means for actuating said collar including a slide carrying said collar, a cam timed in relation with the mandrel,

an arm cooperating with said cam, a link, another arm connected to said link and to said slide, whereby a tube may be forwarded a length along the mandrel, a pan under the mandrel, means for heating the pan, a brush to be reciprocated between the pan and tangential contact with the tube on the mandrel, a rock shaft carrying said brush, a lever arm and a link for operating said rock shaft, a cam turning in timed relation with said mandrel, a fork having an arm actuated by said cam and associated with said last-mentioned link, and another cam with a hand lever for optionally depressing said fork and thereby withholding the brush.

2. In apparatus of the character described having a rotatable mandrel, means for forwarding tubes along said mandrel, a pan under the mandrel, means for heating the pan, a brush to be reciprocated between the pan and tangential contact with the tube on the mandrel, a rock shaft carrying said brush, a lever arm and a link for operating said rock shaft, a cam turning in timed relation with said mandrel, a fork having an arm actuated by said cam and associated with said last-mentioned link, and another cam with a hand lever for optionally depressing said fork and thereby withholding the brush.

3. In apparatus of the character described having a rotatable mandrel, means for forwarding tubes along said mandrel, a pan under the mandrel, a brush to be reciprocated between the pan and tangential contact with the tube on the mandrel, a rock shaft carrying said brush, a lever arm and a link for operating said rock shaft, a cam turning in timed relation with said mandrel, a fork having an arm actuated by said cam and associated with said last-mentioned link, and another cam with a hand lever for optionally depressing said fork and thereby withholding the brush.

4. In apparatus of the character described having a rotatable mandrel, means for forwarding tubes along said mandrel, a liquid supply, a brush to be reciprocated between said liquid supply and tangential contact with the tube on the mandrel, a cam turning in timed relation with said mandrel for reciprocating said brush, and means for optionally depressing said brush.

5. In apparatus of the character described having a rotatable mandrel, means for forwarding tubes along said mandrel, a liquid supply, an applicator to be reciprocated between the liquid supply and contact with the tube on the mandrel, and a cam turning in timed relation with said mandrel for operating said applicator.

DAVID C. SPAULDING, JR.
